UNITED STATES PATENT OFFICE

LEONARD KAY WRIGHT, OF JACKSON HEIGHTS, LONG ISLAND, NEW YORK

REFRIGERATING APPARATUS

Application filed January 4, 1928. Serial No. 244,445.

This invention relates to refrigeration, and more particularly has reference to a refrigerating apparatus.

In the refrigerating devices heretofore employed, much difficulty has been experienced in securing an efficient and economical apparatus. Many of the devices have been of an extremely complicated construction, with numerous movable parts. Consequently the wear and need of repair in such apparatus have been pronounced regardless of whether the machine is of the compression or adsorption type. Particularly the valves, necessary in most apparatus, have caused considerable trouble. Other machines have been of a construction whereby the refrigerant and other agents employed have lodged in various portions of the apparatus, seriously impeding, if not preventing, operation of the process. It has also been necessary heretofore to employ a water cooled condenser in adsorption or absorption apparatus, because of the character of refrigerant used. In pending applications of mine, there are set forth refrigerants that are condensed and liquefied through the use of atmospheric condensers, and it is therefore unnecessary to include in a refrigerating apparatus a condenser of so intricate construction as water condensers. Most of the refrigerators heretofore employed have been ungainly and of a cumbersome size.

An object of this invention is to devise a refrigerating process.

Another object of this invention is to provide a refrigerating apparatus, that is both inexpensive to construct and efficient in operation.

Yet another object of this invention is to provide a valveless refrigerating apparatus equipped with an air cooled condenser.

A further object of this invention is to provide a refrigerating apparatus that can be quickly, easily and cheaply installed in almost any existing ice box, without alteration of the box other than the removal of the ice chamber door.

And still another object is to make use of the space existing at the front and at the top

of the box and locate in this otherwise wasted space the apparatus herein described.

To accomplish the above, and other important objects as will more fully appear, my invention in general comprises a tank adapted to act as both an adsorber and generator, condensing means, a receptacle for the condensate, and evaporating means.

To insure an adequate comprehension of my invention, and wishing it to be distinctly understood that various modifications may be made therein without departing from the spirit, or exceeding the scope, of the appended claims, reference is made to the accompanying drawings, in which similar numerals indicate corresponding parts:

Figure 1 is a view of my complete apparatus with a portion thereof broken away to fully set forth the various elements.

Figure 2 is a view along the line 2—2 of Figure 1 looking in the direction of the arrows.

Figure 3 is a view along the line 3—3 of Figure 1 looking in the direction of the arrows.

Figure 4 is a view along the lines 4—4 of Figure 1 looking in the direction of the arrows.

Figure 5 is a vertical sectional view of a control device.

Figure 6 is a diagrammatic showing of the electrical circuit employed in my apparatus.

There is shown in Figure 1 an icebox 1 of the conventional type, having a compartment 2 ordinarily used for the reception of ice. My invention is adapted to be installed in an ordinary refrigerator, the major portion of the apparatus being inserted in that compartment provided for the storage of ice. To convert such an icebox into an automatic modern refrigerator, it is merely necessary to remove the door of the ice compartment and emplace in the compartment my apparatus. A tank 3, preferably composed of such material that heat may readily be transferred through it, is positioned in the compartment. This tank is water proof and is adapted to contain brine. The tank is provided with a recess 4 which will later be discussed. There is also provided on the tank 3 a stopper or

80

85

90

95

100

pressure tight valve 5 whose use will also be hereinafter set forth. The tank 3 is mounted upon a panel 6 by means of rivets 7, screws, or other suitable fastening means. The panel 6 is provided with an aperture 6' of the same size as the recess 4.

The panel 6, with the attached tank 3, is screwed to another panel 8. The panel 8 extends over the doorway of the ice compartment 2, and also slightly above the top of the box 1. Both of the panels should be constructed of a metal, wood, or other material that has a low heat conductivity, in order that heat from the outside can not be transferred to the tank or ice compartment of the box. Gaskets 9, composed of rubber or other suitable resilient heat insulating material are provided to prevent the entrance of heat into the compartment through the joints. Screws 11, extending through the panel and into the body of the box 1, securely hold the panel in air and heat tight contact with the box.

The panel 8 is also provided with an opening 12 of substantially the same size and corresponding to the opening 11 in the other panel 6. The openings in the two panels may be lined with metal stripping or other suitable material if desired. The recessed portion 4 of the tank 3, and the openings of the two panels, are adapted to receive a tray 13, shown herein as being composed of three compartments, 14, 15 and 16, which tray may be used for the purpose of freezing ice, molding desserts, and other similar uses. Of course, the tray may be composed of one compartment or, as shown in the drawings, may be sub-divided. It is preferable to provide separate trays, so that any one may be removed from the freezing pocket without disturbing the others. Grids may be provided in the trays when it is desired to free cube ice in them. The face 17 of each compartment is recessed as at 18, and within the recess is a handle 19. The handle may be folded within the recess which permits a door 21 to be securely closed over the tray.

The door 21 is supported on the panel 8 by means of hinges 22, preferably of the spring type which maintain the door tightly against the face of the panel. A knob 23, or other appropriate grip, is provided for the door 21. Gaskets 24 of rubber or other suitable material are provided to render the interior of the recess 4 free from the hotter air of the atmosphere. When the tray is removed from the recess, the door will then provide an appropriate closure for the compartment.

At the top of the panel 8 there is supported at right angles another panel 25. The panel 25 is secured to the panel 8 by suitable means, not shown, and extends over the top of the refrigerator 1. Under certain conditions the panel 25 may be omitted. A casing 26 is sup-

ported on the two panels composed of suitable material. The casing 26 is provided at its lower extremity with a screen 27 or other appropriate opening whereby air may enter from the bottom. Near its top the casing is provided with other screens 28 for the emission of air. The casing forms an air tight compartment except for the two screen openings just described, and therefore affords a channel for a draft from the lower to the upper screen.

A curved plate 29 is provided in the rear of the casing, in order to divert all air arising from the lower screen out through the upper screen. This plate prevents the formation of air pockets in the sharp angular portion of the casing. It will also be observed that the casing is curved as at 31, in order to further reduce the formation of air pockets. The casing 26 is provided with a lining 32, composed of asbestos or other suitable heat insulating material, to prevent a heat transfer through the casing.

Supported by arms 33, a tank 34 is positioned within the casing 26 and on top of the box. The tank 34 is substantially cylindrical, with bulged ends 35 and 36 in accordance with standard boiler practice. Of course, under suitable circumstances the particular shape of this tank may be modified. A neck 37 is provided on the tank in which there is securely seated or entreated a cap 38. This cap may be removed in order to fill the tank. The tank is filled with a suitable adsorption agent. While an adsorption agent is preferable, under certain circumstances an absorbent may be employed, or a mixture of both.

A tube 39 extends longitudinally through the tank, the tubing being preferably of material having a high heat conductivity. Within this tubing there is secured a resistance coil 41 or other suitable heating element. While I have shown herein an apparatus adapted for use with electricity, it is not without the purview of my invention to employ some other heating medium, such as gas, oil or steam. Wires 42 are connected to the heating coil and extend to a control mechanism which will be hereinafter described. When current is supplied, the resistance coil 41 heats the contents of the tank.

As is well known, the capacity of an adsorbent or absorbent is a function of its temperature. When a refrigerant is therefore introduced into the tank 34, and the adsorbent is at a low temperature, the refrigerant is taken up by the adsorbent. This adsorption creates a suction in the tank 34, which extends to all parts of the refrigerating system that is in open communication with the tank. On the application of heat to the adsorbent, the refrigerant previously taken up is driven off in the form of a gas.

Extending from the upper part of the tank

34 and joined thereto in a fluid-tight fit, is a pipe 43. A screen is positioned on the end of the pipe to prevent the entrance of adsorbent or foreign matter into the pipe. The pipe 43 is either integral with or connected to a condenser 44. This condenser is of the radiator type, comprising a series of convolutions of pipe 45 through which the refrigerant passes and provided with plates 46 which are soldered or brazed onto the pipes 45. These plates are connected to each convolution of the pipe in a heat exchange relationship, and provide additional dissipating means for the heat evolved during condensation of the refrigerant. Suitable supports 47 are provided for the condenser which are mounted on the panel 25. Under suitable circumstances, any of the conventional air-cooled condensers, equipped preferably with pins or radiating discs, may be used.

The gaseous refrigerant is condensed during the heating cycle. All of the heat that is applied to the adsorbent cannot be retained within the tank 34. The air surrounding the tank 34 which is thus heated passes out of the casing 26 through the screen 28, causing a rush of cooler air from the lower part of the casing to replace the escaping air. During the heating cycle there is therefore a draft through the casing 26, and the condenser is exposed to a constantly changing body of fresh and cooler air. The heat taken up from the condenser 44 by this cool air also causes the air to rise, aiding in the maintenance of a draft.

In Figure 1 there is shown the condenser 44 angularly disposed. It will be observed that air entering the lower screened inlet 27 has a circuitous path to follow, passing over the radiator plates and convoluted condenser several times before its exit from the absorber casing.

Either integral with, or suitably jointed to, the lower or discharge end of the condenser 44, is a pipe 48. This pipe passes through the panels 8 and 6 into the brine tank in an air and heat proof fit, in order that warm air may not enter the interior of the box, and is slightly inclined as shown in Figure 1.

The pipe enters the upper portion of a receiving tank 49 in a fluid tight fit. The receiving tank rests upon the top of the recess 4, although under suitable circumstances its position may be changed. Referring particularly to Fig. 4, it will be observed that the receiving tank is provided with bulged ends 51 and 52. The condensed refrigerant is introduced to the top of the tank and drops to the level of the liquid therein contained.

There is positioned in the receiving tank a safety valve 53 of the rupturing disc type. With certain conditions, another type of valve may be employed. In the event of an excess pressure within the system, which might otherwise result in an explosion, this

safety valve will permit the liquid or gas to flow into the brine solution contained within the tank and thus avert serious accident. Practically all refrigerants when mixed with a brine solution are non-inflammable and non-explosive. Should any of this mixed brine solution and refrigerant escape from the tank 3, there would therefore be no fire hazard.

This brine may be a solution of water and salt, calcium chloride or others of the halogen salts group or may be alcohol, or glycerine, and water may be used. The cap 5 is removed, tank 3 filled with the solution, and the cap 5 replaced. The cap 5 serves to seal the tank 3 so that none of the solution can evaporate. The cap 5 is constructed so that when the pressure within the tank 3 increases it will be lifted or blown out. If the valve 53 ruptures, the brine, in absorbing the refrigerant, increases in volume and forces the cap 5. The mixture of brine and refrigerant can then escape and run down a drain pipe (not shown) from the ice compartment 2.

The solution in the tank 3 also permits a lowering of the temperature below the freezing point of water, and provides a medium whereby these lower temperatures may be more uniformly maintained.

An outlet pipe 54 is joined to the base of the receiving tank 49 in a fluid tight fit, and empties into the base of a well 55.

Referring more particularly to Fig. 5, it will be observed that this well comprises a cylinder 56, provided with an integral base 57, forming a fluid tight container for a liquefied refrigerant 58. The upper portion of this casing is threaded as at 59, and is adapted to receive a correspondingly threaded annular flange 61. The flange is screwed onto the cylinder 56, and by means of welding, brazing or through the use of a thread securing mixture, such as pipe compounds, or litharge and glycerine, a fluid tight joint or union is established. A bearing plate 62 of suitable insulating material is positioned securely on the top of the cylinder 56. The flange 61 itself may be provided with a socket or shoulder to receive the bearing plate 62, or the cylinder may be screwed into the flange until the upper face of the flange is flush with the top of the cylinder.

There fits upon the bearing plate 62, maintaining it firmly against the cylinder and flange, a cap 63, provided with an annular flange 64 coextensive with the flange 61. Bolts 65, or other equivalents, securely hold the cap 63 and the flange 61 in close contact. Litharge, or other suitable means, may be inserted between the flanges 61 and 64 to form a fluid tight joint. A gasket, composed of rubber, asbestos, fibre, or a fluid tight mixture capable of being compressed may be placed between the flanges to maintain a

tight joint, which will also aid in easily dis-
assembling the apparatus. An aperture 66 is
formed in the cap 63, surrounded by a neck
67. Referring to Figure 1, it will be ob-
served that the neck 67 extends through the
top of the brine tank 3 in a fluid tight fit.

In the space formed by the cap 63 and the
bearing plate 62, there is inserted a suitable
insulating compound, such as tar, pitch, or
10 sealing wax. The space is filled with the
compound, either in hot or cold condition,
which serves to insulate the wires and posts.
In the event of rough handling of the ap-
paratus, this insulating material will prevent
15 water or vapor entering the space and short
circuiting the posts or wires. This filler ma-
terial also provides a backing for the bear-
ing plate 62 and strengthens the plate against
the high internal pressures frequently en-
20 countered.

Through the bearing plate 62 there extend
rods 68, only one of which is visible in Fig-
5, which are adapted to serve as supports for
a bulb 69. The bulb 69 is pivoted between
25 the supports and the pivotal means, which
are electrical conductors, extend within the
bulb to approximately one end, as shown at
70 in Fig. 6.

That end of the bulb 69 toward which the
30 pivot extends has fused in it a wire 71. The
opposite end of the wire 71 is connected to a
binding post 72 which extends through the
bearing plate 62. A cable 73, composed of
35 two wires 74 and 75, extends through the
neck 67 into the cap 63. The wire 74 is
joined to one or both of the rods 68, and the
wire 75 is joined to the binding post 72.

The electrical connections for the bulb 69,
40 may be as shown in Figure 5, or it may be
preferable to eliminate the post 72 and wire
71, in which event each of the posts 68 serves
as an electrical conductor, the bulb being
equipped with two pivotal means extending
45 into each of the rods 68, and which also ex-
tend within the bulb to within a short dis-
tance of one end. The pivotal means serve to
conduct electricity from the supports 68 to
one end of the bulb. An electric circuit is
50 established when the mercury flows into this
end and bridges the two pivotal means. By
providing this alternative arrangement, it is
necessary to drill only two holes through the
bearing plate 62, thus strengthening that
55 member.

Mercury 76 is inserted in the bulb 69, ap-
proximately half filling it, after which the
bulb is either evacuated or an inert gas under
considerable pressure is forced into the tube
after evacuation of the air. This prevents
60 oxidation and serves to quench the arc inci-
dent to making or breaking the circuit. The
pressure within the bulb also considerably
strengthens the bulb notwithstanding the
high pressures to which it is frequently sub-
65 jected.

When the tube 69 is tilted so that the mer-
cury falls to that end of the tube in which
is fused the wire 71, the mercury covers both
the pivotal means and the wire 71, establish-
ing an electrical circuit. When the tube is
70 tilted in the opposite direction, the electrical
connection between the pivotal means and the
wire 71 is broken. The cable 73 is joined
to a suitable source of electrical supply, either
a conventional city circuit or an appropri-
75 ate battery or generator. It will therefore
be seen that the tube 69 serves as a switch
to open or close the circuit.

There is fused to the bulb 69 a ring 77.
Through this ring there extends a shaft 78
80 provided with beads 79 above and below the
ring. A bead 81 is also provided on the shaft
78 near the top, and a bead 82 is fixed to the
shaft near the base.

Slidably mounted on the shaft 78 is a float
83. This float comprises a hollow sphere
or vessel of some other shape provided with
a tube 84 extending through it. The tube
84 is mounted in the bulb in a water and
pressure tight fit, and it is through the tube
90 84 that the rod 78 extends. Ample clear-
ance within the tube 84 is allowed for the
rod 78, so that movement of the float 83
on the rod 78 is perfectly free.

The float 83 is provided with another tube
85 extending within it in a fluid and pres-
sure tight fit. The tube 85 extends to ap-
proximately the lowest part of the float 83,
and on its exterior end is bent as shown at
86. The tube 85 is adapted to equalize the
pressures existing on the outside and within
the float. Considerable difficulty has been
experienced heretofore with various floats
used, for the marked differences between the
internal and external pressures has crushed
105 the floats. By equalizing the exterior and
interior pressures, this disadvantage, attend-
ant in the prior floats, has been obviated.
The tube 85 also serves to maintain the in-
terior of the float free from any liquid.
Should a refrigerant spray or liquid enter
110 the float 83, it will be forced out through
the tube 85 when there is a reduction in pres-
sure in the system, for the higher pressure
existing within the float 83 will force the liq-
uid within the float through the tube 85.

The level of the condensed refrigerant 58
in the well 55 will be the same as that exist-
ing in the receiving tank 49 and the pos-
ition of the float 83 will therefore register the
liquid level in the tank 49. As the level of
the refrigerant in the tank 49 rises, the float
83 will rise on the shaft 78, and when the
tank 49 is approximately full of condensed
125 refrigerant, the float 83 will contact with the
bead 81. This will tilt the float 69, causing
the circuit to be broken. With the conse-
quent cooling of the adsorbent in the gen-
erator 34, further vaporization of the re-
130

frigerant in the generator 34 will be discontinued.

As the liquid level decreases, the float 83 falls on the shaft 78, finally contacting with the bead 82. Further downward movement of the float 83 causes the shaft 78 to tilt the mercury tube 69, which closes the circuit and commences the heating of the adsorbent.

The operation of the mercury tube 69 is shown in more detail in Figure 6. The mercury tube 69 and wires 74 and 75 form part of a circuit between a source of electricity 87 and the resistance coil 41. The mercury 76 is shown as covering both the pivoting means 15 70 and wires 71, closing the circuit.

Should the alternative form of bulb be employed, the circuit is closed when the mercury blows to that end of the bulb to which the pivoting means extend. When the mercury covers both of the pivoting means, an electric current will flow from one of the supports 68 and to the pivoting means, thence through the mercury to the other pivoting means and other support 68.

25 Suitably mounted in the base of the cylinder 56 in a fluid and pressure tight fit is a pipe 88. The pipe 88 extends about the well 55 in a spiral formation, as more clearly shown in Figures 1 and 2, forming an evaporating coil 89. A bracket 91 is secured to the brine tank 3 by means of bolts 92 or other suitable means, serves to support the evaporating coil 89. The upper end of the coil 89 is connected to a T-joint 93. The opposite arm of the T-joint is joined to a pipe 94, which is mounted in the top of the cylinder 56. The stem of the T-joint 93 is connected to a section of pipe 95 which is mounted in the top of the tank 49. It will be observed that the pipes 88 and 94 and coil 89 are in open communication with the well 55, and that the liquid level within the evaporator 89 is the same as that existing in the well 55 and the tank 49.

45 From the foregoing the operation of my invention is apparent. The cap 38 is removed and the adsorbent is placed in the generator 34. The necessary refrigerant is also introduced to the system through the neck 37, and the cap 38 is replaced. Assuming that the adsorbent is cool, all of the refrigerant will be taken up by the adsorbent. There will be no liquid refrigerant in the tank 49, the well 55, or the evaporating coil 89. The float 83 will therefore be contacting with the bead 82. The rod 78 will be forced downwardly, and the bulb 69 will be in the position shown in Figure 6. This 60 will close the circuit, and the resistance coil 41 will be supplied with electricity when the current is turned on. The heat generated by the resistance coil will permeate the adsorbent contained in tank 34, causing it to drive off the adsorbed refrigerant in the form

of a gas. The gaseous refrigerant will pass out of the tank 34 through the pipe 43.

Heating the adsorbent will build up within the tank 34 an autogenous pressure. This pressure, of course, extends to all of the system in open communication with the tank 34. The gas in the pipe 43 will therefore be forced downwardly through the pipes 45 of the condenser 44.

The heat escaping from the tank 34 will pass out of the casing 26 through the screen 28, and the cooler air which rushes to replace the hotter escaping air will cause a draft to pass over the condenser 44. The incoming cooler air passes over the pipes and plates of the condenser twice before escaping through the screen 28, so that the condenser has an adequate exposure to the cooling effect of the fresh air. This cooling is enhanced by the plates 46 which are joined transversely to the convolutions of pipe 45. When a suitable refrigerant is employed, the lower temperatures produced in the condenser by virtue of this cooling are sufficient to liquefy the refrigerant.

By the time the refrigerant reaches the discharge end of the condenser all or practically all of it has been liquefied, and passes through the pipe 48 to the tank 49. From the tank the liquefied refrigerant flows 95 through the pipe 54 to the well 55. A portion of the refrigerant passing through the pipe 54 enters the pipe 88 and evaporating coil 89. When the liquid levels in the well 55 and evaporator 89 extend as high as the 100 base of the tank 49, any subsequent rise in the level is simultaneous with an equal rise in the level of liquid in tank 49.

During the condensation and storage of the refrigerant in the tank 49, well 55, and evaporating coil 89, the complete system is subjected to a comparatively high pressure, sufficient to maintain the refrigerant in the tank 49, well 55, and the coil 89 in the liquid state. Continued condensation of the gaseous refrigerant fills the tank 49, and also the well 55. During the rise of the refrigerant in the well 55, the float 83 likewise rises, and when the tank 49 is approximately filled with liquid refrigerant, the level in the well 55 will be such that the float 83 pushes against the bead 81. This causes the tube 69 to be tilted so that the circuit is broken. The heating of the resistance coil 41 is therefore stopped, and a fall in the temperature of the 110 adsorbent ensues.

The refrigerating cycle is now commenced. As stated, the tank 49, the well 55, and the evaporating coil 89 are all approximately substantially filled with a liquid refrigerant. 125 So long as there is a high pressure in the system, the refrigerant will remain in the liquid phase. With termination of the heating of the adsorbent, there is a consequent reduction in pressure throughout the system. 130

The lowering of the temperature of the adsorbent creates a suction by the adsorbent. This suction is felt throughout the system, and there consequently begins a vaporization of the liquefied refrigerant. This vaporization occurs to a certain extent in the tank 49 and the well 55, but the most pronounced vaporization and refrigerating effect occur within the coil 89. The vaporized refrigerant will pass from the well 55 into the pipe 94 through the T-joint 93, and pipe 95, and the vaporized refrigerant, from the coil 89, will pass directly through the pipe 95 to the tank 49.

From the pipe 95 the refrigerant enters the tank 49, and from thence, together with the gas from the refrigerant in tank 49, passes out through the pipe 48 into the coils 45. It will be observed that the coils 45, while acting as a condenser during the heating cycle, fail to perform such function during the refrigerating cycle. There is not the same draft through the casing 26 during the refrigerating cycle as during the heating cycle, for the tank 34 is not giving off any appreciable heat. There is also, of course, a much lower pressure in the condenser 44 during the refrigerating cycle than during the evaporating cycle, and the refrigerant therefore will remain in a gaseous form and pass through the pipe 43 to the tank 34 where it is taken up by the adsorbent. Even during a refrigerating cycle, the adsorbing tank 34 will remain slightly warm, so that a limited draft will flow through the casing 26. This draft will remove the latent heat of the refrigerant which has been assimilated and removed from the refrigerating chamber.

With vaporization of the refrigerant, there is an attendant fall in the liquid levels within the tank 49, the well 55, and the coil 89. When practically all of the refrigerant has been evaporated, the float 83, falling on the shaft 78, will contact with the bead 82. Any further fall of the float 83 will cause the rod 78 to be pulled downwardly and the mercury bulb 69 will be turned so that the mercury covers the pivoting means and the wire 71. This closes the electrical circuit, and the resistance coil 41 is supplied with electricity.

The heating cycle, as described above, will then be repeated.

The advantages of my invention are apparent. The apparatus requires no attention after the operation is commenced.

My invention is not only automatic in operation, but it maintains in the refrigerating compartment a substantially uniform temperature. With an increased atmospheric temperature, or temperature within the refrigerator, there will be a more rapid vaporization of the refrigerant during the refrigerating cycle, which will consequently increase the refrigerating effect. On the other hand, if the compartment 2 needs little re-

frigeration, the lower temperature in the compartment 2 retards vaporization of the refrigerant. Should the pressure within the system increase, the valve 53 will permit the refrigerant to escape into the brine solution contained in the tank 3, in which it is absorbed, forming a non-inflammable and non-explosive solution. An added precaution against explosion, is the fact that the additional area of tank 3 with its brine content is sufficient to assimilate the amount of refrigerant contained in the system.

The apparatus herein shown and described is valveless. This is a decided advantage over the refrigerators heretofore used, for much difficulty has been experienced by reason of the valves wearing out, need of repair, and clogging by the refrigerant. By eliminating valves there is no call for lubrication, which has also seriously handicapped the prior refrigerators.

It will be observed that the apparatus is easy and economical to construct, yet it is of a rugged type that is capable of long and continued operation.

It also eliminates all connections, such as gas or water, and requires only a pliable connection to a source of electrical energy if attached to a city circuit. If the source of electrical energy is self-contained in the refrigerator, there is no need for any connection whatsoever. By using an air cooled condenser and an appropriate refrigerant, the necessity for water is eliminated, materially increasing the simplicity of the apparatus and reducing the cost of operation.

Where I use the word "adsorption" it is to be taken as comprehending "absorption" as well. It is also to be understood that where I have used the word "adsorbent" in the specification or claims it is to cover likewise "absorbent" or a combination of "adsorbent and absorbent."

It is of course obvious that various modifications may be made in the structure set forth in the drawings and described herein, but I wish to have such drawings and description taken as exemplary merely and not definitive, the scope of my invention being determined merely by the appended claims.

I claim:

1. A refrigerating apparatus comprising a generator, a condenser, a receiving tank, all three elements operatively associated, and a safety valve positioned on the receiving tank.

2. In a refrigerating apparatus, a refrigerating compartment, at one side of the compartment a tank adapted to receive a refrigerant, at the opposite end of the compartment a well connected with the tank by a fluid line, and an evaporating coil adjacent the well and supplied with a fluid from the well.

3. A refrigerating apparatus comprising

an adsorbent generator, a condenser in open communication therewith, a tank adapted to receive the condensate, and an evaporating coil and a well in communication with a tank,
5 the adsorbent generator being adapted to be operated by means controlled by the level of the condensate in the well.

4. In a refrigerating apparatus, a refrigerating compartment, at one side of the compartment a tank adapted to receive a refrigerant, the tank being in open communication with an adsorber-generator, at the opposite end of the compartment a well connected with the tank by an open fluid line,
15 means within the well to control the operation of the adsorber-generator, and an evaporating coil adjacent the well, the receiving tank, well and evaporating coil being in free communication.

20 In testimony whereof I affix my signature.

LEONARD KAY WRIGHT.
